UNITED STATES PATENT OFFICE.

THEODORE H. SORLIEN, OF MINNEAPOLIS, MINNESOTA.

CEILING-BED.

1,116,854.

Specification of Letters Patent.

Patented Nov. 10, 1914.

Application filed March 30, 1914. Serial No. 323,236.

To all whom it may concern:

Be it known that I, THEODORE H. SORLIEN, a citizen of the United States, residing at Minneapolis, in the county of Hennepin and 5 State of Minnesota, have invented certain new and useful Improvements in Ceiling-Beds; and I do hereby declare the following to be a full, clear, and exact description of the invention, such as will enable others 10 skilled in the art to which it appertains to make and use the same.

My invention relates to improvements in ceiling beds of the type disclosed and claimed in my U. S. Letters Patents No. 15 1,065,740, of June 24, 1913, and No. 1,069,585, of August 5, 1913, and allowed application filed October 29, 1913, under Serial Number 797,996; and, to this end, it consists of the 20 novel devices and combinations of devices hereinafter described and defined in the claims.

In the accompanying drawings, which illustrate the invention, like characters indicate like parts throughout the several views.

25 Referring to the drawings:—Figure 1 is a side elevation of the improved ceiling bed in a lowered position, supported by its folding legs; Fig. 2 is a plan view, on an enlarged scale, of the foot end of the bed, 30 some parts being broken away, some parts removed, and with the legs in a folded position; Fig. 3 is a detail view in longitudinal vertical section taken through the foot end of the bed, as shown in Fig. 1, on an enlarged scale; Fig. 4 is a detail view partly 35 in plan and partly in horizontal section, showing a portion of the spring frame and the connected ends of the longitudinally adjustable leg-actuating rock shaft at the foot 40 end of the bed; Fig. 5 is a detail view in transverse vertical section taken on the line $x^6 x^6$ of Fig. 4, on an enlarged scale; Fig. 6 is a detail view in transverse section taken 45 on the line $x^6 x^6$ of Fig. 4, on an enlarged scale; Fig. 7 is a detail view in longitudinal vertical section taken through the head end 50 of the bed, as shown in Fig. 1, on an enlarged scale; and Fig. 8 is a view corresponding to Fig. 7, but showing the parts in a folded position.

The numerals 1, 2 and 3 indicate, respectively, the end rails, side rails and corner posts which form the rectangular frame of the improved ceiling bed. Permanently secured to the under side of this bed frame is

a bottom panel 4, which, when the bed is raised into an opening formed in the ceiling, for receiving the same, closes said opening, as fully shown and described in my above referred to patents and application. Secured to the rectangular marginal edge of the bottom panel 4 is a molding 5, which extends horizontally outward from the bed frame and completely closes the opening in the ceiling, outward of the bed. The improved bed is raised and lowered by four chains 6, secured at their lower ends to the upper ends of the four posts 3 of the bed frame. These chains 6 are preferably operated, for raising and lowering the bed, as shown in my above identified application, but it is, of course, understood that any other suitable means may be provided.

Head and foot boards 7 and 8, respectively, are secured to the ends of the bed frame by depending metal straps 9 rigidly secured, at their upper ends, to the corner posts of said boards, and with their lower ends pivotally secured at 10 to the inner faces of the bed frame posts 3, at a point below the upper ends thereof. By thus pivotally connecting the head and foot boards, the same may be moved from an upright position, as shown in Figs. 1 and 7, into substantially horizontal folded positions within the bed frame and entirely below the upper marginal edge thereof, as shown in Fig. 8. When in upright positions, the head and foot boards are held against outward swinging movement by the engagement of the lower ends of their end posts with the bed frame posts 3. The end posts of the head and foot boards, when in upright positions, form extensions of the bed frame posts 3, and are provided with longitudinally extended channels 11 for receiving the chains 6, as best shown in Figs. 2 and 7.

In order to permit the improved ceiling bed to be stored in a relatively shallow opening in the ceiling, the bed spring 12, having a marginal rectangular frame 13 constructed of angle bars, is mounted within the bed frame for vertical movement toward and from the bottom panel 4. When the bed is not in use, and is stored in the ceiling opening, the bed spring is supported directly on or very close to the bottom panel 4. In this position of the spring, the mattress and bedding are supported thereon entirely within the bed frame, with the head and foot boards

folded thereon; but when the bed is in use, the spring is supported high enough above the bottom panel 4 to be effective.

To raise and lower the bed spring, the 5 same is supported from the upper ends of four folding legs 14. When the bed is in use, the same is supported from the floor by these legs 14, which are provided with intermediate horizontally extended trunnions 10 15. These trunnions 15 are pivotally and slidably mounted in horizontally extended slots or pockets 16 formed in the side rails 2 of the bed frame.

Opposite legs 14 are connected in pairs 15 for simultaneous swinging movement, longitudinally of the bed, to and from operative positions, by longitudinally extensible rock shafts. Each of these rock shafts comprises a pair of aligned tubular members 20 17 rigidly secured, at their outer ends, to the upper ends of the legs 14. These rock shaft members 17 are journaled, with freedom for endwise sliding movement, in bearings 18 rigidly secured to the end members 25 of the spring frame 13 and in the projecting ends of the side members of said spring frame, as best shown in Figs. 3, 7 and 8. The inner ends of the rock shaft members 17 are spaced apart, as best shown in Fig. 30 4, and slidably mounted for endwise movement in a rectangular tubular sleeve coupling 19 which is held against endwise movement between the bearings 18.

When the legs 14 are folded, the same 35 may be seated so as to be completely out of the way when the bed is moved into the ceiling opening. For moving the pairs of legs 14 simultaneously into and out of the pockets 16, the rock shaft members 17 are 40 connected, at their inner ends, for reverse endwise movement, by a pair of rack bars 20 and a cooperating pinion 21. This pinion 21 is journaled within and to the intermediate portion of the coupling 19, and 45 the racks 20 mesh with opposite sides thereof. Each rack bar 20 is provided, at one end, with a shank 22 and a rectangular head 23. The shanks 22 are telescoped into the inner ends of the rock shaft members 17, and are rigidly secured thereto by pins 24. The rectangular heads 23 slidably work within the coupling 19, thus permitting free endwise movement of the rock shaft members 17, but locking the same together for 55 common rotation with said coupling. Obviously, by pulling outward on one of the pairs of legs 14, the opposite leg will receive a like movement through the longitudinal separation of the rock shaft. After the 60 legs 14 are removed from the pocket 16, the same may be simultaneously swung downward into operative positions. The pockets 16 are enlarged at their intermediate portions, to afford hand holes 25, through 65 which may be grasped the legs 14. When

the bed is to be moved into the ceiling opening, the legs 14 on one side of the bed are swung into longitudinal alignment with the pockets 16, and then, by pressing inward on the same, will, together with the legs on 70 the opposite side of the bed, be moved into their respective pockets 16.

From the foregoing description, it is evident that the bed spring, mattress, bedding and head and end boards may be all folded within a compact space within the bed frame, thus permitting the bed to be stored in a relatively shallow opening in the ceiling. In moving the bed spring to and from operative positions, the leg journals 15 rotate and slide in the pockets 16. As best shown in Fig. 1, the legs are preferably spread, in order to prevent the same from accidentally folding when the bed is in use.

What I claim is:—

1. A ceiling bed comprising a frame having a bottom panel, a spring, means for raising and lowering said bed bodily, and means for adjusting said bottom panel and spring vertically, one in respect to the other. 80
2. A ceiling bed comprising a frame having a bottom panel, a spring, means for raising and lowering said bed bodily, folding legs for supporting said bed when in a lowered position, and connections between said legs and spring whereby said spring will be raised and lowered, with respect to said bottom panel, during the folding movements of said legs. 90
3. A ceiling bed comprising a frame having a bottom panel, a spring, means for raising and lowering said bed bodily, and folding legs pivotally connected at their upper ends to said spring, said legs being intermediate fulcrumed to said bed frame with freedom for longitudinal sliding movement in respect thereto. 100
4. A ceiling bed comprising a frame having a bottom panel, a spring, means for raising and lowering said bed bodily, folding legs pivotally connected at their upper ends to said spring, said legs being intermediate fulcrumed to said bed frame with freedom for longitudinal sliding movement in respect thereto, and an end board pivotally secured to said bed frame for folding movement from an upright position to a substantially horizontal position within said bed frame, arranged to be moved from said horizontal position into an upright position by the raising movement of said spring, with respect to said bottom panel, and to be locked by said spring in said upright position. 110
5. A ceiling bed comprising a frame having a bottom panel, a spring, means for raising and lowering said bed bodily, folding legs pivotally connected at their upper ends to said spring, said legs being intermediate fulcrumed to said bed frame with free- 120
- 125
- 130

dom for longitudinal sliding movement in respect thereto, and head and foot boards pivotally secured to said bed frame for folding movements from upright positions 5 to substantially horizontal positions within said bed frame, arranged to be moved from said horizontal positions into upright positions by the raising movement of said spring, with respect to said bottom panel, 10 and to be locked by said spring in said upright positions.

6. A ceiling bed comprising a frame having a bottom panel, means for raising and lowering said bed bodily, including flexible 15 connections secured to said bed frame, an end board pivotally secured to said bed frame for folding movement from an upright position to a substantially horizontal position within said bed frame, said end 20 board having channel end posts for receiving said flexible connections when said end board is in an upright position, and stops for holding said end board in an upright position against outward folding movement.

25 7. A ceiling bed comprising a frame having a bottom panel, means for raising and lowering said bed bodily, including flexible connections secured to said bed frame, an end board pivotally secured to said bed 30 frame for folding movement from an upright position to a substantially horizontal position within said bed frame, said end board having channel end posts for receiving said flexible connections when said end 35 board is in an upright position, stops for holding said end board in an upright position against outward folding movement, and means for locking said end board in an upright position against inward folding 40 movement.

8. A ceiling bed comprising a frame having a bottom panel, means for raising and lowering said bed bodily, an end board pivotally secured to said bed frame, at a point 45 below the upper edge thereof, permitting said end board to be folded from an upright position into a substantially horizontal position within said bed frame, said bed frame and end board having coöperating 50 stop surfaces for holding said end board in an upright position against outward folding movement.

9. A ceiling bed comprising a frame having a bottom panel, means for raising and lowering said bed bodily, including flexible 55 connections secured to said bed frame, an end board pivotally secured to said bed frame, at a point below the upper edge thereof, to permit said end board to be 60 folded from an upright position into a sub-

stantially horizontal position within said bed frame, said bed frame and end board having coöperating stop surfaces for holding said end board in an upright position against outward folding movement, said 65 end board having channel end posts for receiving said flexible connections when said end board is in an upright position.

10. In a ceiling bed, the combination with a frame, of means for raising and lowering 70 the bed bodily, a rock shaft journaled on said bed and comprising a pair of alined members having their inner ends spaced apart, bed-supporting legs secured on the outer ends of said rock shafts, a rectangular 75 coupling sleeve held against endwise movement and in which are seated for endwise sliding movement the inner ends of the members of said rock shaft, a pinion journaled in said sleeve, and a pair of rack bars 80 meshing with opposite sides of said pinion, each of said rack bars having at one end a rectangular head slidably working in said sleeve, and having a shank secured to the inner end of one of the sections of said rock 85 shaft, said sleeve and rectangular heads connecting the members of said rock shaft for common rotary movement, but with freedom for independent endwise sliding movement toward and from each other. 90

11. In a ceiling bed, the combination with a frame, of means for raising and lowering said bed bodily, a spring having a marginal frame, a longitudinally extensible rock shaft journaled on the frame of said spring, 95 and folding legs intermediately fulcrumed on the frame of said bed for limited longitudinal sliding movement in respect thereto, the upper ends of said legs being rigidly secured to said rock shaft. 100

12. In a ceiling bed, the combination with a frame, of means for raising and lowering the bed bodily, a spring having a marginal frame, a longitudinally extensible rock shaft journaled on the frame of said spring, 105 longitudinally extended pockets in the side rails of the frame of said bed, and folding legs intermediately fulcrumed in said pockets with freedom for longitudinal sliding movement in respect thereto, the upper 110 ends of said legs being secured to said rock shaft, said legs, when folded, being adapted to be seated in said pockets.

In testimony whereof I affix my signature in presence of two witnesses.

THEODORE H. SORLIEN.
